UNITED STATES PATENT OFFICE.

RANDOLPH P. HULL, OF NORWALK, OHIO.

DESIGN FOR AN UMBRELLA-TIP.

SPECIFICATION forming part of Design No. 31,240, dated July 18, 1899.

Application filed December 31, 1897. Serial No. 665,235. Term of patent 14 years.

To all whom it may concern:

Be it known that I, RANDOLPH P. HULL, a citizen of the United States, residing at Norwalk, in the county of Huron and State of Ohio, have invented and produced a new and original Design for Tips for Umbrella-Ribs; and I do hereby declare the following to be a full, clear, and exact description of the invention, such as will enable others skilled in the art to which it appertains to make and use the same.

In the accompanying drawings, which form part of this specification, Figure 1 is an enlarged detail perspective view of the tip. Fig. 2 is a side view thereof, and Fig. 3 is a top view.

The leading features of my design consist in an approximately spherically-shaped head having a shank projecting therefrom formed substantially as shown in the accompanying drawings and as herein described.

The tip consists of a rounded head 1 and the shank 3. The head 1 is approximately spherical in shape, with a flattened face 2 next and around the shank. The shank 3 extends 25 or projects outwardly from the head, and for a part of its length it is cylindrical in form. Toward its free end the shank is flattened, tapered, and widened, thus giving it a wedge-shaped extremity 4, and this widened flattened part of the shank exceeds in width the diameter of the cylindrical part of the shank. 30

What I claim as new is—

The design for an umbrella-tip substantially as herein shown and described. 35

In testimony whereof I affix my signature in presence of two witnesses.

RANDOLPH P. HULL.
